UNITED STATES PATENT OFFICE

HERBERT B. TAYLOR, OF ROCHESTER, NEW YORK, ASSIGNOR TO GENERAL RAILWAY SIGNAL COMPANY, OF ROCHESTER, NEW YORK

TRAIN CONTROL

Application filed July 23, 1929. Serial No. 380,379.

This invention relates in general to automatic train control systems for railways, and has more particular reference to an axle-driven reversing switch for use in such systems.

Whether the train control system in question be intermittent or continuous, inductive or conductive, or the like, it is generally considered desirable to have a train subject 10 to the automatic control when going in the direction of traffic, whether the engine or tender be in the lead and to have it free from the automatic control, when going against the direction of traffic, whether the engine 15 or tender be in the lead.

While applicable to various types of automatic train control, there will here be considered merely by way of example, what is necessary to automatically produce the above desired conditions in connection with an automatic intermittent inductive train control system in which a receiver is mounted on each side of a vehicle, and inductors are mounted along the trackway on the right side 25 only.

On considering the forward and backward operation in the direction of traffic, it will be observed, that in changing from forward to backward operation, the direction of rotation 30 of the vehicle axles will be reversed, and at the same time the sides of the vehicle, relative to the trackway also will be reversed. Hence, an instrumentality which will respond 35 to a change in direction of rotation of the vehicle axles, so as to cut one receiver out of the control circuit and the one on the opposite side in, will function to maintain the train with automatic control under the two conditions being considered. When moving opposite to the normal direction of traffic, whether going backward or forward, this same instrumentality will in each case relieve the train from automatic control.

With the above and other considerations 45 in mind, it is proposed according to this in-

vention, to provide an axle-driven reversing switch which will function to reverse a set of contacts upon reversal of the direction of rotation of the car axle.

Further objects, purposes, and characteris- 50 tic features of the invention will appear as the description progresses, reference being had to the accompanying drawings, showing, solely by the way of illustration one specific embodiment of the inventive concept. 55 In the drawing:

Fig. 1 is a sectional view on line 1—1 of Fig. 2 viewed in the direction of the arrows;

Fig. 2 is a side elevation of a device embodying the present invention with parts cut away 60 to more clearly show the structure;

Fig. 3 is a sectional view on line 3—3 of Fig. 2 viewed in the direction of the arrows;

Fig. 3A is a sectional view on line 3A—3A of Fig. 2 viewed in the direction of the ar- 65 rows;

Fig. 4 is a sectional view on line 4—4 in Fig. 2 viewed in the direction of the arrows.

Referring now to the drawings, a dotted portion 1 (see Figs. 1 and 4) represents the 70 end portion of a pony truck axle of a locomotive, with tap bolts 2 securely fastening the main rotating drive member 3 to the pony truck axle, having located the central position by placing the circular flange 3^a within a 75 groove which has been cut into the axle by means of a lathe.

The reversing switch mechanism, as includ- 80 ed within the present invention, is held in an upright position, resisting the tendency to rotate, by the torque rod or conduit 4 being suitably clamped to the frame F of the locomotive, and also serving the purpose of a conduit for the necessary lead wires which are associated with such a reversing switch. 85

The rotating drive member 3, is journaled in a two part casing composed of casing mem- 90 bers 5 and 6 which are suitably secured by bolts 7 and nuts 8 having the usual lock washers. This rotating drive member 3 is suit-

ably lubricated by oil passing through oil feeders 9, with the oil reservoir within the cavity of the rotating drive member 3, which is further inclosed within its casing members 5 and 6 by the cover 10 being held down upon the gasket 11 by the tap bolts 12 secured with the usual lock washers. This cover 10 has a thread plug 13 so located that the cavity within the drive member 3 can be filled with suitable lubricating oil.

There is a worm gear 3^b formed on the periphery of the rotating drive member 3, which drives the spiral gear 14 at a much reduced speed on its axle 15 which is journaled at each end in the bearing bushings 16 and 17 and has riveted upon it at one end the trip member 18. The bearing bushing 17 is suitably held within the case 6 with the thrust washer 17^a intervening between said bearing bushing 17 and gear 14. The bearing bushing 16 is held against the end of the axle 15 with the thrust washer 16^a intervening between the bearing bushing 16 and the gear 14, by the adjusting nut 19 which is locked into place by the lock nut 20. The bearing bushing 16, the adjusting nut 19 and lock nut 20 have suitable passages for allowing suitable lubricating oil to pass through to the bearing, which lubricating oil is retained in a cavity within the grease cup 21 being sealed by the gasket 22.

The trip member 18 has two arms with rollers 23 and 24 on axles 25 and 26 at the ends of their respective arms, (see Figs. 3 and 3A) which engage at certain times the dogs 27 and 29. These dogs 27 and 29 are biased by the spring 28 and are mounted on the movable rocker arm 30, which has its bearing pin 30^b journaled in case 6 with pin 31 pressed firmly by spring 32 into a groove in said bearing pin 30^b to hold the arm 30 in place. Also, the pins 30^c and 30^d are integral with the arm 30 and furnish limits for the biased dogs 27 and 29.

The arm 30 also has a toothed sector 30^a integral with it, which engages a toothed dog 33 that cooperates with a toggle link and spring combination 34, 34^a and 35 which causes said dog 33 to assume either of two extreme positions. The link and spring combination 34, 34^a and 35 is supported by a member 36 which is suitably secured to the casing 6 by tap bolts 37, while the toothed dog 33 is suitably secured to shaft 38, which shaft 38 is supported by members 39 and 40 suitably secured to casing 6. Insulated from said shaft 38 but rockable with it are the contact sectors 41 that, for example, when in the extreme right hand position (see Fig. 2) make connections between contact figures 42 and 43, also between figures 44 and 45, and again when the contact sectors 41 are in an extreme left position, contact will be made between figures 46 and 47, also between 48 and 49. Thus, it can be easily seen that the con-

tact sectors 41 are biased to their extreme positions by the toggle provided by links 34 and 34^a and spring 35.

In this particular form shown in the drawing, there have been shown four different sets of contact fingers which may be used as desired under varying circumstances, depending on the circuits to be controlled in a particular case; however this number can of course be varied according to the conditions.

The contact fingers 42, 43, 44, 45, 46, 47, 48, and 49, are securely attached to insulating blocks 50 (see Fig. 1) by binding posts 51 having suitable terminal nuts, with said blocks 50 secured on the top of bosses 6^a by the tap bolts 53, considering of course that there can be no possible connection between the binding posts 51 and said bosses 6^a or tap bolts 53.

This contact mechanism along with the tripping mechanism are housed within the casing 6 with a cover 54 tightly secured by gasket 55, being firmly pressed into place by means of hinges and a spring hasp which are considered of minor importance and therefore are not shown.

It will be noted here, that the torque rod 4 provides means whereby the reversing switch, as included within the present invention, is prevented from rotating in the direction of the pony truck axle denoted by the dotted portion 1. However, as the locomotive wheels pass over uneven trackway, the locomotive frame F will sway in respect to the pony truck axles, which motion is provided for by the torque rod 4 being pivoted in respect to the casing 6 (see Figs. 2 and 4) by a suitable bearing surface provided on the torque rod 4 to set within a supplementary bearing surface within the casing 6, and secured in this position by the pin 56 fitting within a groove provided in the torque rod 4. The pin 56 is suitably held into position by cotter keys or otherwise.

Operation.—It is assumed, that the drawings show the reversing switch in the normal conditions for forward running with the reversing switch mounted upon the right hand side of the locomotive and with the trackway inductors on the right hand side of the track facing in the direction of traffic; hence, the reversing switch will have connections made between fingers 42 and 43 also between contact fingers 44 and 45 thus having the train control receiver on the right hand side of the locomotive connected in the circuit. Thus, the locomotive may run forward with normal traffic with train control or against normal traffic without train control providing of course the engine is leading the tender and other cars in either case.

With the above outlined conditions obtaining, motion of the car in a forward direction is transmitted to the tripping arm 18 through the drive member 3, gear 14 and axle 15. This

will cause the tripping arm to revolve in a counter-clockwise direction (see Figs. 3 and 3A) as indicated by the arrow designated N, thus causing no change in contact connections, as the dog 27 is passively or inoperably pushed aside by the rollers 23 and 24 increasing the bias on spring 28 while the dog 29 is entirely cleared. Thus, the locomotive is provided with train control for forward running in the direction of traffic or is relieved of train control when travelling against the direction of traffic, due to the fact, that the trackway inductor is on the opposite side of the track from the car carried receiver.

Now let us assume, that the locomotive is travelling backwards either in a direction against normal traffic or in a direction with normal traffic. In either case, the tripping member 18 will rotate in a clockwise direction (see Figs. 3 and 3 A), as indicated by the arrow designated R. In this case the roller 24 will revolve toward dogs 29 and 27, clearing dog 29 and actively or operably pushing dog 26 until it has made arm 30, toothed sector 30^a, toothed dog 33 and link 34 assume their opposite extreme positions, at which time the dog 27 will clear the roller 24, while dog 29 will not be entirely cleared, but will let the rollers 23 and 24 pass by causing merely an increase in bias on spring 28 in the same manner as dog 27 before the motion had been reversed. The motion of toothed dog 33 changing to its opposite extreme position, is transmitted to the contact sectors 41 so that they assume an extreme left hand position (see Figs. 1 and 2) at which time contact is made between contact fingers 46 and 47, also between contact fingers 48 and 49. This position of the contact sectors 41 has connected the left hand receiver of the train control apparatus, in addition to disconnecting the right hand receiver. Thus, the apparatus is now connected so that the locomotive may run backward against the direction of normal traffic without train control, or with the direction of normal traffic with train control.

It should be noted, that the contact sectors 41 are arranged to close the new circuit before breaking the old one, so that at all times the control mechanism is connected to a receiver, thus preventing an unnecessary brake application which would occur if the receiver circuit were broken.

The above rather specific description of one form of this invention, is given solely by the way of illustration, and is not intended in any manner whatsoever, in a limiting sense, as obviously the invention can be embodied in many different physical forms, and is susceptible of numerous modifications, and all such forms and modifications are intended to be included in this invention as come within the scope of the appended claims.

Having described my invention, I now claim:—

1. In a reversing switch mechanism for train control systems, a shaft, means operatively connecting said shaft to the end of a vehicle axle, an electric switch capable of assuming either of two extreme positions, means operating said electric switch to an opposite extreme position upon reversal of rotation of said shaft, and means holding said switch in its extreme positions independently of said operating means.

2. In a reversing switch mechanism for train control systems, a casing, a shaft in said casing, means operatively connecting said shaft to the end of a vehicle axle including, a main drive member connected to the end of said vehicle axle and having a worm gear integral therewith, a spiral gear mounted on said shaft and engaging said worm gear, means supporting said casing including bearing supports on said main drive member, and a torque rod preventing rotation of said casing on said bearing supports, an electric switch capable of assuming either of two extreme positions, and means operating said switch to an opposite extreme position upon reversal of rotation of said shaft.

3. In a reversing switch mechanism for train control systems, a shaft, means operatively connecting said shaft to a vehicle axle, an electric switch capable of assuming either of two extreme positions, means operatively connecting said shaft and said switch to move the switch to a corresponding extreme position upon the reversal in the direction of rotation of the shaft, said means being effective to move said switch only during the movement thereof, and means for holding said switch in its extreme position independently of its operating means.

4. In a reversing switch mechanism for train control systems, a shaft, means operatively connecting said shaft to a vehicle axle, an electric switch capable of assuming either of two extreme positions, and means operatively causing said electric switch to assume an opposite extreme position upon reversal of rotation of said shaft including, a positively engaging ratchet upon initial reversal of said shaft and a passively engaging ratchet upon continued rotation in one direction.

5. In a reversing switch mechanism for train control systems, a shaft, means operatively connecting said shaft to a vehicle axle, an electric switch capable of assuming either of two extreme positions, and means operatively causing said electric switch to assume an opposite extreme position upon reversal of rotation of said shaft including, a rocker arm associated with said electric switch, two dogs mounted on said rocker arm and biased to extreme positions, trip arms mounted on said shaft which positively engage one of said dogs upon reversal of rotation of said shaft to cause said rocker arm to assume an opposite extreme position.

6. In a reversing switch mechanism for train control systems, a shaft, means operatively connecting said shaft to the end of a vehicle axle, an electric switch capable of assuming either of two extreme positions and means operatively causing said electric switch to assume an opposite extreme position upon reversal of rotation of said shaft including, a rocker arm associated with said electric switch and capable of assuming either of two extreme positions, two dogs mounted on said rocker arm and biased to extreme positions, trip arms mounted on said shaft one of which positively engages one of said dogs only upon initial reversal of rotation of said shaft to cause said rocker arm to assume an opposite extreme position and thereafter allowing all of said trip arms to passively engage the other of said dogs until rotation is again reversed.
7. In a reversing switch mechanism for train control systems, a casing, a shaft in said casing, means operatively connecting said shaft to the end of a vehicle axle including, a main drive member connected to the end of said vehicle axle and having a worm gear integral therewith, a spiral gear mounted on said shaft and engaging said worm gear, means supporting said casing including bearing supports on said main drive member, and a torque rod preventing rotation of said casing on said bearing supports, an electric switch capable of assuming either of two extreme positions, means operating said switch to an opposite extreme position upon reversal of rotation of said shaft, including a rocker arm associated with said electric switch and capable of assuming either of two extreme positions, two dogs mounted on said rocker arm being biased to extreme positions, and trip arms mounted on said shaft one of which positively engages one of said dogs only upon initial reversal of rotation of said shaft and all of which thereafter passively engage only the other of said dogs until direction of rotation of said shaft is again reversed.
8. In a reversing switch mechanism for train control systems, a shaft, means operatively connecting said shaft to a vehicle axle, an electric switch capable of assuming either of two extreme positions, and means operatively causing said electric switch to assume an opposite extreme position upon reversal of rotation of said shaft including a toothed dog operably connected to said electric switch, a toggle combination biasing said toothed dog to either of two extreme positions, a rocker arm centrally pivoted, a toothed sector integral with said rocker arm and engaging said toothed dog, two pivoted dogs respectively mounted on each extremity of said rocker arm, said pivoted dogs being biased to extreme positions, trip arms mounted on said shaft any one of which is adapted to operatively engage a corresponding one

of said pivoted dogs upon initial reversal of rotation of said shaft to actuate said rocker arm to an opposite extreme position, whereby the one of said pivoted dogs engaged by said trip arm is thereafter disengaged from that trip arm and the remaining arms, and whereby said other pivoted dog is actuated to an operating position in readiness for the next reversal of rotation of said shaft.

In testimony whereof I affix my signature.
